GEORGE W. BEADLE, OF NEW YORK, N. Y., ASSIGNOR OF TEN ONE-HUNDREDTHS TO DELAVEN SMITH, OF LAKE FOREST, ILLINOIS, AND TEN ONE-HUNDREDTHS TO EDWARD P. RUSSELL, OF CHICAGO, ILLINOIS.

DETACHABLE BOTTLE-CAP.

1,153,477

Specification of Letters Patent. Patented Sept. 14, 1915.

Application filed April 2, 1915. Serial No. 18,741.

To all whom it may concern:

Be it known that I, GEORGE W. BEADLE, a citizen of the United States, residing at New York city, in the county of New York and State of New York, have invented certain new and useful Improvements in Detachable Bottle-Caps; and I do hereby declare the following to be a full, clear, and exact description of the invention, such as will enable others skilled in the art to which it appertains to make and use the same.

This invention relates to spring pressed detachable bottle caps and has for its object to provide a closure for vessels in general, but especially adapted for bottles, which will be comparatively inexpensive to construct and more convenient and efficient in action than those heretofore proposed.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views—Figure 1 is a diagrammatic elevational view of a bottle neck provided with my invention; Fig. 2 is a sectional view of the parts shown in Fig. 1; Fig. 3 is a bottom plan view of the cap removed from the bottle mouth; Fig. 4 is a plan view of a blank employed in the manufacture of the cap; Fig. 5 is a plan view of the spring wire employed in connection with the blank shown in Fig. 4; and Fig. 6 is a modified form of the spring wire construction.

1 indicates any suitable vessel the mouth of which is to be closed, in this instance shown as a bottle, and which mouth is preferably provided with the usual overhanging lip 2 and 3 represents the body portion of a metal cap adapted to close the mouth of the bottle 1. The said metal cap is preferably formed from a blank such as shown in Fig. 4 which is preferably stamped out of sheet metal, but which may of course be formed out of any other material. As shown the blank is provided with the radially projecting members or flanges 5 separated by the spaces 6, and is formed into a cup shape in suitable dies by bending the blank or striking the same up on the dotted line 7, to form the overhanging lip or wall 8 of the cap. A

spring wire such as 9 is conveniently placed 55 on the outside of the wall 8, whereupon the radially projecting members or lips 5 may be curled upwardly and outwardly over the said wire 9 to firmly hold it in place, as will be readily understood from Figs. 1 to 4 of 60 the drawings. When desired the said walls 8 may near their outer edges be given a slightly inclined set or inward bend as shown at 10 in Figs. 1 and 2 so as to enable the cap to snugly hug the projecting lip or shoulder 65 2, as will be readily understood. This last named action is further facilitated by the spring wire 9, as will now be made clear. Said wire may be formed into a ring as illustrated in Fig. 5 and its two ends 11 and 12 70 suitably interlocked or joined together as shown, or its two ends may be twisted together as at 13, as illustrated in the modified form of the invention shown in Fig. 6.

In the form shown in Fig. 5 the middle 75 portion of the wire 9 is formed into a spiral shape as illustrated at 14 and the ends 15 and 16 of the spiral 14 are led in opposite directions so that they overlap each other, as will be readily understood. It results 80 from this construction that the wire 9 being of spring material if the opposing body portions 17 and 18 of the spiral are pressed together between the fingers for example, the loop portion 9 of the wire will be opened out 85 so that owing to the spaces 6 between the ears 5 the wall portions 8 of the cap will be slightly extended and the cap may thereupon be readily detached from the overhanging lip 2. The detaching action is also facilitated by the fact that while the body portions 17 and 18 of the spiral are thus grasped they afford a hold which enables one to lift upwardly on the cap with a considerable leverage so that the cap may be readily 90 snapped off the bottle mouth. On the other hand, owing to the spring action of the spiral 14 the ears 5 of the cap are immediately drawn together as soon as the pressure on the said spiral is released and the bent 100 over portions of said ears being rounded as shown, the cap may be readily snapped back onto the bottle mouth whereupon the said spring spiral 14 holds it firmly in place.

A cork disk such as 20 or other suitable 105 packing material is conveniently provided on the inside of the cap to facilitate the making of a tight joint.

In the modified form of construction shown in Fig. 6 the spiral 21 is the same as the spiral 14 except that the ends of the wire 9 are twisted or otherwise secured together as at 13.

It will be readily understood that by making the wire 9 of a greater or less strength and by properly selecting a material for making the cap 3 which has a proper stiffness, any desired tight fit may be produced on the mouth of the vessel 1 or any ease of removal of the cap may be had.

It is obvious that those skilled in the art may vary the details of construction as well as the arrangement of parts without departing from the spirit of my invention and therefore I do not wish to be limited to the above disclosure except as may be required by the claims.

20 What I claim is:

1. In a snap closure for a vessel mouth having a holding bead, the combination of a cup shaped member having a resilient flange adapted to be snapped over said bead; and a 25 spring wire rigid with said flange provided with a coiled portion adapted when com-

pressed to expand said flange, substantially as described.

2. In a snap closure for a vessel mouth having a holding bead the combination of a 30 cup shaped member having a resilient flange adapted to be snapped over said bead; and a spring wire rigid with said flange provided with a compressible integral, bent portion adapted when compressed to expand said 35 flange, substantially as described.

3. In a snap closure for a vessel mouth having a holding bead the combination of a 40 cup shaped member having a resilient flange adapted to be snapped over said bead; and a 45 spring wire rigid with said flange provided with a compressible spirally wound integral portion adapted when compressed to expand said flange and to serve as finger holds for readily removing the closure, substantially as described.

In testimony whereof I affix my signature in presence of a witness.

GEORGE W. BEADLE.

Witness:

SAUL W. LEVY.
